ATTORNEY

UNITED STATES PATENT OFFICE

CHARLES LAURENCE BURDICK, OF LONDON, ENGLAND, ASSIGNOR TO THE AEROGRAPH COMPANY LIMITED, OF LONDON, ENGLAND

SPRAYING APPARATUS

Application filed January 28, 1928, Serial No. 250,276, and in Great Britain May 9, 1927.

My invention relates to machines for spraying or atomizing liquids and may be used for distributing colours or paints on various surfaces, or for medical purposes or wherever a nice control is required in order that the delivery of the liquid may be capable of being produced in the form of a very fine spray. Such sprays are usually made with a valve for compressed air and a needle valve for the control of the liquid situated in the liquid delivery port, both valves being under the control of a single operating member, which in my invention would have two movements, a movement of depression for the air valve and a rocking movement for the control of the quantity of liquid to be delivered.

My invention consists in a novel arrangement of parts whereby the air valve is kept open until the liquid valve is practically closed thus preventing liquid which is not thoroughly atomized from being thrown out on to the surface which is being operated upon.

The invention further consists in means for setting the liquid valve to deliver a definite small quantity whenever the air valve is opened; this is accomplished by providing a regulating device or stop by means of which the needle valve is held back from completely closing the delivery port.

A further feature of the invention consists in an arrangement of the fulcrum and the operative point of the finger lever in such a manner that the delivery of the liquid into the escaping jet of compressed air is at first very gradual and increases in volume as the finger lever is drawn back, thus giving the operator a very nice control over the delivery of small quantities of colour or liquid which are required for fine lines or delicate shading and the like.

The invention has for its object to provide a convenient means for insuring that the occurrence of the two movements of the operating member shall only take place in the desired order, both when opening and closing the valve.

The invention further comprises the improved arrangement of parts whereby ef-

ficiency in operation is obtained, provision for cleaning and repair is facilitated and economy of production is obtained.

The invention is illustrated in the accompanying drawing in which

Fig. 1 represents the device in cross section and Fig. 2 is a detail of the valve controlling device.

Referring now to the form illustrated, the spray comprises a hollow body 1 having a cup or receptacle 2 for liquids and a handle portion 3. Underneath the body is formed a boss 4 having a channel 5 for compressed air and an internal thread 6 for the attachment of an air valve casing 7 to which is secured a nipple 8 for attachment to the compressed air conduit. Opposite the boss 4 the body is provided with a cavity 9 surmounted by a slot 10 in the upper wall thereof. The forward opening of the body is threaded to receive the liquid and air delivery nozzle including the seating 11 for the needle valve 12 which controls the liquid supply and passes through a gland 13 in the forward part of the cavity 9. Secured to the needle valve is a squared abutment block 14, the rear portion of which provides an abutment for the valve controlling spring 15. Within the cavity 9 is slidably mounted a valve control mechanism shown separately in Fig. 2. This generally comprises a cylindrical casing 20 having an upper slot 21 and a lower slot 22 and formed as an extension to a block 23 having a squared hole 24 to receive the abutment 14 and provided with a forwardly-extending cam-shaped member 25 comprising a small bent lug or strip.

The valve controlling member comprises a finger disc 26 secured to a pair of slotted arms 27 articulated by means of a pivot 28 to an air valve operating rod 29 having a reduced lower end 30 which is slidably within the lower slot 22. A pivot pin 31 slides within the slots 32 of the arms 27 and supports a needle valve operating plate 33 having a slot 33a in its transverse face to receive a cam-shaped member 25. The slotted arms 27 support a transverse abutment pin 35 carrying a roller 36 which normally lies in front of the end of the cam-shaped member 25.

When the parts are assembled as shown in Fig. 1, the air valve operating rod 29 is housed within a tube 40 having an upwardly extending lug 41 projecting into the slot 22 and adapted to serve as a fulcrum to the lower end of the shoulder plate 33. It is an important part of the invention that the front end 14^a of the squared abutment block 14 on the needle valve 12 is rounded as illustrated in Fig. 1. The air valve 50 in the casing 7 is spring controlled and carries a pin 51 adapted to be engaged by the reduced end 30 of the rod 29 as clearly shown in Fig. 1.

15 An angle piece 52 having a bifurcated lower end 53 is secured to the block 23 by means of a grub screw and is engaged in a groove 54 formed in the head of a screw 55 adapted to be adjusted in a threaded hole in

20 the body 4.

The operation of the device is as follows, the parts lying in the position illustrated in Fig. 1 in which case the liquid valve and the air valve are shut.

25 The finger plate 26 is depressed forcing down the rod 29 and opening the air valve 50. Until this movement is completed the arms 27 cannot be rocked rearwardly owing to the engagement of the roller 36 with the cam-shaped member 25, so that the liquid valve cannot be opened until the air valve is fully released. Conversely the liquid valve must shut while the air valve is still fully opened, thus preventing liquid which is not 30 thoroughly atomized from being thrown out on to the surface which is being operated upon in a spot or blob.

When the air valve is fully opened the arms 27 are rocked in a rearward direction 40 about the pivot 28. The pin 31 has by this time ridden to the top of the slots 32 and the rearward rocking movement of the arms 27 causes the shoulder plate 33 to retract the abutment block 14 and needle valve 12 thus

45 opening the liquid delivery port. During this movement, the shoulder plate 33 fulcrums about the projection 41 and it will be realized that owing to the curved end face 14^a of the abutment block 14 the contact between the plate and the block gradually shifts from the lower part of the face to the upper part of the face so that for a given increment of displacement in the rearward direction of the plate 33, the needle valve will be opened by a 50 progressively increasing amount. The initial opening therefore of the liquid delivery valve is at first very gradual, but increases more rapidly as the finger plate is drawn further backwards.

55 It will be appreciated that the front abutment for the finger plate comprises the front edge of the slot 21 and that consequently if the block 23 and cylinder 20 are drawn back by the intermediary of the fork 53 by with- 60 drawing the screw 55 the slotted arms 27 will

be rocked so as to open more or less the valve 12 and this part of the appliance is accordingly brought into use when it is desired either to maintain the liquid delivered at a fixed small value for a prolonged time or alternatively to provide a minimum delivery in connection with the variable use of the device.

I claim:

1. In a spray device having independent air and liquid control valves, a control member mounted for movement in one direction to operate one of the valves and for movement in another direction for operating the other of said valves, and means whereby the control member is locked against movement in one of such directions until its movement in the other of such directions has been accomplished.

75 2. A spray device including independent air and liquid control valves and a control member for said valves, said member being mounted for longitudinal movement to control the air valve and for swinging movement to control the liquid valve, and means whereby the control member is locked against swinging movement to govern the liquid control valve until its longitudinal movement for controlling the air valve has been accomplished.

80 3. A spray device including independent air and liquid control valves and a control member for operating said valves, said control member having a longitudinal movement to open the air valve and a swinging movement to open the liquid valve, and means to lock the control member against swinging movement to open the liquid valve until longitudinal movement of such control member to open the air valve has been accomplished, 85 said locking means serving to hold the air valve open through the control member in any position of the control member tending to hold the liquid valve open.

100 4. A spray device including independent air and liquid control valves and a control member for operating said valves, said control member having a longitudinal movement to open the air valve and a swinging movement to open the liquid valve, and means to lock the control member against swinging movement to open the liquid valve until longitudinal movement of such control member to open the air valve has been accomplished, 105 said locking means serving to hold the air valve open through the control member in any position of the control member tending to hold the liquid valve open.

110 5. In a spray device for spraying or atomizing liquid and having air and liquid control valves operated by a single member having two distinct movements to open said valves, a cam-shaped member, an axially slid able rod to open the air valve, an operating member 115

- for said liquid valve having pivotal and sliding connection with said rod, means on said rod to engage said cam-shaped member and prevent rocking movement when said rod and operating member are in one relation, and said cam-shaped member preventing the change in relation of said rod and operating member when said rod has been depressed and the operating member has been rocked.
6. In a spray device for spraying or atomizing liquid, a body member, air and liquid control valves operated by a rocking finger piece articulated to a pivot slidable in said body member, a cam-shaped member fixed relatively to said body member and an abutment on the finger piece to normally engage said cam-shaped member to prevent rocking movement of said finger piece when the pivot thereof is in a predetermined relation and to engage said abutment when the finger piece has been depressed and rocked to prevent lift of the abutment.
7. A spray device including a hollow body, an air valve for controlling the passage of air therethrough, a liquid valve for controlling the passage of liquid therethrough, and control mechanism for said valves including a cylindrical element designed to seat in a recess in the body, a control member mounted for longitudinal and swinging movement in said element, an operating rod connected to the control member to engage and operate the air valve in the longitudinal movement of the member, a cam-shaped member carried by the element, and a stop on the control member to engage the cam-shaped member and prevent swinging movement of the control member when said control member is in normal position, said stop moving below the cam-shaped member following longitudinal movement of the control member to permit swinging movement of such control member for operating the liquid governing valve.
8. A spray device including a hollow body, an air valve for controlling the passage of air therethrough, a liquid valve for controlling the passage of liquid therethrough, and control mechanism for said valves including a cylindrical element designed to seat in a recess in the body, a control member mounted for longitudinal and swinging movement in said element, an operating rod connected to the control member to engage and operate the air valve in the longitudinal movement of the member, a cam-shaped member carried by the cylindrical element, and a stop on the control member to engage the cam-shaped member and prevent swinging movement of the control member when said control member is in normal position, said stop moving below the cam-shaped member following longitudinal movement of the control member to permit swinging movement of such control member for operating the liquid governing valve.
